No. 14,980

14,980

Apr. 29, 1884

UNITED STATES PATENT OFFICE.

WILLIAM P. KELLOGG, OF TROY, NEW YORK.

DESIGN FOR A CURRY-COMB BACK.

SPECIFICATION forming part of Design No. 14,980, dated April 29, 1884.

Application filed November 17, 1883. Term of patent 7 years.

To all whom it may concern:

Be it known that I, WILLIAM P. KELLOGG, of the city of Troy, county of Rensselaer, and State of New York, have invented a new and ornamental Design for the Backs of Curry-Combs, of which the following is a specification.

My design relates to the form and ornamentation of the backs of curry-combs, as shown in the accompanying photograph, forming a part of this specification. This design is produced by the form of the body-bars B, as arranged in the back at right angles to the side bars, the side bars, B', having scalloped outer edges, a hand-bar having its inner end arranged with up-curves, and therefrom divided to produce the bifurcated bars B² B³, each of which is curved outwardly from the point of

division to join and subtend the side bars, with all of the said bars excepting where up-curves are made in the hand-bar being in a horizontal plane.

Having thus described my invention of a design, what I claim, and desire to secure by Letters Patent, is—

The design for a curry-comb back, consisting of the body-bars B, the side bars, B', having scalloped outer sides, the handle-bar provided with upward curves at one end and curved bifurcated bars B² B³ at the other, as described and shown.

WM. P. KELLOGG.
